(57) **CLAIM**

The ornamental design for a rack-mounted fishing rod holder for bicycle, as shown and described.

DESCRIPTION

FIG. 1 is a side perspective view of a rack-mounted fishing rod holder for bicycle showing my new design; and,

FIG. 2 is a rear perspective view thereof.

The broken lines showing a bicycle seat, two wing nuts, and a bracket attaching the rod holder to the bicycle rack in FIG. 1 and a bicycle seat, two wing nuts, a bracket attaching the rod holder to the bicycle rack and a fishing rod in FIG. 2 illustrate the portions of the design that form no part of the claim.
